UNITED STATES PATENT OFFICE.

ALBERT E. PENFOLD, OF BIRMINGHAM, ENGLAND, ASSIGNOR TO THE DUNLOP RUBBER COMPANY, LIMITED, OF REGENTS PARK, LONDON, ENGLAND.

DESIGN FOR A GOLF BALL.

Application filed September 11, 1922. Serial No. 3,689. Term of patent 14 years.

To all whom it may concern:

Be it known that I, ALBERT ERNEST PENFOLD, a subject of the King of Great Britain, residing at Manor Mills, Salford Street, Aston, Birmingham, in the county of Warwick, England, have invented a new, original, and ornamental Design for Golf Balls, of which the following is a specification, reference being had to the accompanying drawing, forming a part thereof.

Figure 1 is a view of a golf ball drawn on an enlarged scale showing my new design applied to the surface of the ball.

Figure 2 is another view of the golf ball as seen after turning the ball from the position shown in Figure 1 on the horizontal axis X—X through an angle of 90 degrees.

Figure 3 is a sectional view of the golf ball taken on the line X—X of Figure 1.

I claim—

The ornamental design for a golf ball as shown.

ALBERT E. PENFOLD.
